UNITED STATES PATENT OFFICE.

REESE B. EARLY, OF RIVERSIDE, CALIFORNIA.

LOOM LOCK.

Application filed May 12, 1925. Serial No. 29,710.

The present invention relates to loom locks or fasteners and it has for its principal object to provide an efficient, reliable, and simple loom lock or fastener for securing looms used for insulating wires in position in terminal boxes or in other places where looms or flexible tubes are to be secured in position for the purpose of insulating the electrical wire connections in systems or in devices of different kinds to prevent pulling away of the loom from the part or device from which the wire carrying the electric current is to be insulated:

Another important object of the invention is to provide a loom lock or fastener of this nature which will securely hold the loom from slipping on the wire.

Another very important object of the invention is to provide a loom lock or fastener of this nature which may be quickly put in place or detached as desired.

A still further very important object of the invention is to provide a device of this nature which may be manufactured at a relatively low cost and yet be strong, durable, effective, and otherwise well adapted to the purpose for which it is designed.

With the above and numerous other objects in view as will appear as the description proceeds, the invention resides in certain novel features of construction as will be hereinafter more fully described and claimed.

In the drawing:

Figure 1 illustrates a loom fastener containing the features of my invention, and shows the same in connection with a terminal box or the like for securing looms therein to prevent withdrawal of the loom.

Figure 2 is a detail section therethrough taken substantially on the line 2—2 of Figure 1.

Figure 3 is a perspective view of the loom fastener showing the same before applied to the loom.

Referring to the drawing in detail it will be seen that 1 designates a terminal box which is provided with a plurality of openings 2, or of course may be provided with a plurality of "knock out" blanks 3 of a form well known in this art. The wire 3' is inserted through one of the openings formed by punching one of the knock out blanks from the box, together with the insulating loom 4 which surrounds the wire

in the usual manner. These looms and wires are secured by the fasteners indicated generally by the letter F, located within the terminal box as is shown clearly in Figures 1 and 2. The loom fastener F, however, 60 may be placed in any suitable position for properly engaging and anchoring the loom. In the present instance it is placed in that position which will prevent the movement of the loom which it is desired to restrain. 65 It is obvious that it may be placed both on the inside and the outside of the member through which the wire passes, if desired, in order to prevent movement of the loom in either direction. The position shown 70 herein, however, is the position that the loom fastener is commonly placed, namely, to prevent the end of the loom from being withdrawn from the box.

My improved loom fastener is formed 75 from wire which is substantially square in cross section. The wire is formed in a circular looped central portion 6 having oppositely disposed curved arms 7 extending therefrom and terminating in loops 8. The 80 fastener is placed about the loom and pliers are engaged with the looped portion 6 thereof so that the same may be bent to a relatively oval shape so as to securely engage the loom so that the fastener cannot slip 85 thereon, and so that the loom cannot slip on the wire. It is obvious that the slipping of the fastener on the loom is prevented by the square cross sectional construction of the wire from which the fastener is formed. 90 The fastener may be very easily removed by engaging the terminal loops 8 with suitable tools or with the fingers or bending the arms away from the loom at which time the fastener may be easily and quickly removed. 95 The fastener having the features of this invention will not cut into the loom to any appreciable extent, and there will, therefore, be no danger of short circuiting the wire 3 as in those fasteners where incisions are made in the loom.

It is thought that the construction, efficiency, and advantages of my fastener will now be clearly understood by those skilled in this art without a more detailed description thereof. It is obvious that the present embodiment of the invention has been disclosed merely by way of example in order to illustrate one way of obtaining the features of advantage enumerated as desirable 100 105 110

in the statement of the invention and the above description. It will be apparent that numerous changes in the details of construction, in the materials and in the size, may 5 be resorted to without departing from the spirit or scope of the invention as herein-after claimed or sacrificing any of its advantages.

Having thus described the invention, what 10 I claim as new and desire to secure by Letters Patent is:—

1. A loom fastener formed of a circular looped wire substantially square in cross section, its ends bent to form laterally extending yielding arms.

2. A loom fastener formed of a circular looped wire substantially square in cross section, its ends bent to form laterally ex-

tending yielding arms, and terminating in loops.

3. A loom fastener formed of a circular looped wire substantially square in cross section, its ends bent to form laterally extending yielding arms, and terminating in loops, said arms being curved throughout 25 their lengths.

4. A loom fastener formed of a looped wire having a flat portion with sharp edges and terminating in arms extending laterally.

5. A loom fastener formed of a looped wire having a flat portion with sharp edges and having its ends bent to form laterally 30 extending yielding arms.

In testimony whereof I affix my signature.

REESE B. EARLY.
